UNITED STATES PATENT OFFICE.

WILLIAM M. ANDERSON, OF MINNEAPOLIS, MINNESOTA.

COVE-PLATE FOR BEAMS AND CEILINGS.

1,120,009.

Specification of Letters Patent.

Patented Dec. 8, 1914.

Application filed July 21, 1913. Serial No. 780,150.

To all whom it may concern:

Be it known that I, WILLIAM M. ANDERSON, a citizen of the United States, residing at Minneapolis, in the county of Hennepin and State of Minnesota, have invented certain new and useful Improvements in Cove-Plates for Beams and Ceilings; and I do hereby declare the following to be a full, clear, and exact description of the invention, 10 such as will enable others skilled in the art to which it appertains to make and use the same.

My invention relates to improvements in cove plates for use in the construction of beams and ceilings and, to this end, it consists of the novel construction and arrangement of parts hereinafter described and defined in the claim.

In the accompanying drawings, which 20 illustrate the invention, like characters indicate like parts throughout the several views.

Referring to the drawings:

Figure 1 is a perspective view of one corner of a room having secured to the ceiling and walls thereof a beam and coving constructed in accordance with my invention; Fig. 2 is a transverse vertical section, taken through the coving; Fig. 3 is a transverse vertical section, taken through the beam; and Fig. 4 is a detail view on an enlarged scale, showing the construction of one of the so-called cove plates.

The numerals 1 and 2 indicate, respectively, the walls and ceiling of a room.

Referring first to the construction of the improved cove plates 3, the numeral 4 indicates two pieces of buckram of different weave pasted together and sized. Buckram 40 is carried in stock in this form. To the exposed face of the buckram of finer weave is pasted a sheet of heavy coarse paper 5, such as red rosin paper. In securing the buckram 4 to the red rosin paper 5, the 45 paste is preferably applied to the buckram and the meshes thereof completely filled therewith. One face of the red rosin paper 5 is then moistened with water and pressed onto the pasted side of the buckram 4, preferably by rolling. The parts thus assembled

are then allowed to dry. After drying, a thin finishing paper 6 is pasted on the exposed face of the red rosin paper 5. The red rosin paper 5 is preferably moist with water and the paste is applied to the red 55 rosin paper or the finish paper. As the finish paper 6 dries, it shrinks, thereby warping or curving the entire cove plate 3 to substantially its correct form.

Referring now to the construction of the 60 coving, the upper longitudinal edge of one of the coving plates 3 is secured to the ceiling 2 by small nails and the edge thereof is covered by narrow molding 7 nailed to the ceiling 2. The lower longitudinal edge of 65 the coving is nailed to the walls 1 and a furring strip 8 is preferably interposed between the coving plate 3 and the wall 1. The corner of the coving plate 3 and furring strip 8 is covered by molding 9 which is 70 nailed to the walls 1.

In constructing ceiling beams, the sides thereof are formed by spacing two of the cove plates 3 laterally apart and securing their upper longitudinal edges to the ceiling 75 2 by nails. These longitudinal edges are then covered with a molding 10 similar to the molding 7. A board 11 forming the bottom of the beam is secured to the lower longitudinal edges of the cove plates 3 by 80 nails. The corners formed by the cove plates 3 and the bottom board 11 are also covered by corner moldings 12, similar to the molding 9.

The finish paper 6 may be grained to represent different woods or it may be plain paper painted, stained, or enameled, as desired, depending on the finish of the rest of the room. The moldings 7, 9, 10 and 12 and also the bottom board 11 may be constructed from expensive woods or from cheap woods covered with a finish paper 13 of the same design as that applied to the cove plates 3. In some instances, it might be desirable to use a picture molding in 95 place of the molding 9 of the coving.

Beams and coving constructed in accordance with my invention can be put in place very quickly and are of comparatively small cost to manufacture.

What I claim is:

A cove plate made up of two pieces of buckram of different weaves pasted together, a heavy, coarse paper pasted on the exposed side of the buckram of finer weave, and a finishing paper pasted on the exposed side of said coarse paper.

In testimony whereof I affix my signature in presence of two witnesses.

WILLIAM M. ANDERSON.
